ABSTRACT: Two flowrate control valves for hydraulic systems having respective rotary throttle valves are joined back-to-back coaxially in tandem along the axis of the throttle valves, which comprise cutouts positioned in tandem on a common valve body at symmetrical positions with respect to the axis, one of the flowrate control valves being provided with a bypass check valve. The resulting combination is a duplex flowrate control valve operable by a single manipulation and which can be used to vary the speed of hydraulic fluid-driven devices without the adverse occurrences unavoidably accompanying control with a single control valve.

DUPLEX FLOWRATE VALVE FOR PRESSURIZED FLUIDS

BACKGROUND OF THE INVENTION

This invention relates generally to hydraulic (fluid pressure) systems and more particularly to a new duplex flowrate control valve for pressurized fluid in hydraulic systems.

In hydraulic system organizations such as that wherein hydraulic fluid delivered from a pump is supplied by a power-driven, reciprocating switching valve alternately to the two heads of a double-acting hydraulic motor of piston-and-cylinder type to cause the piston rod of the piston to undergo reciprocating motion, it is frequently necessary to change the speed of the piston rod. This can be accomplished by varying the flowrate of the fluid flowing through the hydraulic circuit, and two or three methods of using a single flowrate control valve for varying this flowrate are already in use.

The use of a single flowrate control valve, however, is accompanied by certain disadvantageous occurrences such as increase in the speeds of the driven parts with decrease in the load on the motive power motive power means or a rise in the fluid temperature and excessive load on the motive power means as will be described more fully hereinafter.

SUMMARY OF THE INVENTION

It is an object of the present invention to eliminate the above mentioned disadvantageous occurrences accompanying the use of a single flowrate control valve in a hydraulic configuration of the above described character.

According to the present invention, briefly summarized, there is provided a duplex flowrate control valve for pressurized fluids characterized by the combination therein of two flowrate control valves having respective throttle valves and valve boxes joined together in tandem alignment with one valve box structurally inverted back-to-back, relative to the other valve box, one of the control valves being provided with a bypass check valve, the throttle valves being joined integrally in coaxial tandem arrangement to form a single combined valve body having cutouts constituting operative surfaces of the throttle valves and symmetrically positioned with respect to the axis of the combined valve body, the combined valve body being inserted in corresponding valve chambers within the valve boxes.

The nature, principle, details, and utility of the invention will be more clearly apparent from the following detailed description with respect to a preferred embodiment of the invention when read in conjunction with the accompanying drawing, in which like parts are designated by like reference numerals.

BRIEF DESCRIPTION OF THE DRAWING

In the drawing:

FIG. 1 is a schematic diagram showing an example of a hydraulic circuit including flowrate control valves, which in combination constitute the duplex control valve of the invention, a hydraulic driving member, and a driven member;

FIG. 2 is a relatively enlarged, longitudinal sectional view of a changeover valve in the system illustrated in FIG. 1;

FIGS. 3 and 4 are relatively enlarged sectional views of examples of two flowrate control valves suitable for combination to form a duplex control valve according to the invention;

FIG. 5 is a front view of the duplex flowrate control valve;

FIG. 6 is an enlarged perspective view showing a single combined valve body of the throttle valves of the duplex control valve; and

FIGS. 7 and 8 are cross sections respectively taken along the planes indicated by lines (7)-(7) and (8)-(8) in FIG. 6.

DETAILED DESCRIPTION

Referring first to FIG. 1, the hydraulic system illustrated therein consists, essentially, of a hydraulic circuit comprising a power-driven reciprocating changeover valve 3, a flowrate

control valve A, a hydraulic motor 7 with a piston 7a, and a flowrate control valve B provided with a check valve 8 functioning as a bypass valve. A pump 2 driven by an electric motor 1 is connected to supply pressurized fluid to the changeover valve 3.

When pressurized fluid is thus delivered from the pump 2 to the power-driven reciprocating changeover valve 3, shown in detail in FIG. 2, the fluid is delivered alternately from delivery ports 4 and 5 of the valve 3. At the same time, return-flow pressurized fluid is discharged from a discharge port 6, and piston 7a is caused to undergo reciprocating motion.

The speed of this reciprocating motion is varied, according to the invention, by installing the flowrate control valve A and the flowrate control valve B with the check valve 8 in the hydraulic circuit as shown in FIG. 1. The valve B as shown in detail in FIG. 4 is similar in construction and operation to the valve A as shown in detail in FIG. 3 except that it includes the check valve 8. Valves A and B are provided respectively with similar throttle valves 9 and 10 and similar compensator valves 12 and 12a.

The flowrate control valves A and B differ in that, whereas a decrease in the degree of opening of the throttle valve 9 in the control valve A causes a decrease in the flowrate of fluid flowing out from the hydraulic circuit and an increase in the flowrate of the fluid within the circuit, a decrease in the degree of opening of the throttle valve 10 in the control valve B causes a direct reduction of the flowrate of the fluid within the circuit. Therefore, if the control valves A and B were to be used together but respectively in their independent states, it would be necessary to turn their throttle valves 9 and 10 in respectively opposite directions for accomplishing control of the flowrate of the fluid through the circuit.

Accordingly, in a preferred embodiment of the invention, the two throttle valves 9 and 10 are constructed integrally in tandem as illustrated in FIG. 6 or coupled in coaxial tandem arrangement to form a single combined valve body in which circumferential recesses or cutouts 9a and 10a, respectively, of valves 9 and 10 are in symmetrically disposed left and right positions as indicated in FIGS. 7 and 8.

Furthermore, the valve box of one of the control valves A and B as shown in FIGS. 3 and 4 is inverted structurally relative to the other, that is, as though one valve box were turned through 180° of angle about a vertical axis, and the two valve boxes are thus joined back-to-back in tandem to receive the aforesaid combined valve body of throttle valves 9 and 10. By turning a knob 11 affixed to one end of the combined valve body, flowrate control due to both control valves A and B can be carried out by a single manipulation.

Each of the aforementioned compensator valves 12 and 12a operates to maintain constant the difference between the pressures on the upstream and downstream sides of the corresponding throttle valve and to stabilize the flowrate of the fluid through the hydraulic circuit.

When only the control valve A is used, the flowrate control is accomplished by discharging fluid out of the hydraulic circuit. For this reason, a rise in the fluid temperature does not occur, and the electric motor 1 for driving the pump 2 is not subjected to excessive load. However, the speeds of driven parts such as the piston rod 7a disadvantageously increase when the load decreases. On the other hand, while the use of only the control valve B is effective in the control of the speed of the driven parts, it is accompanied by disadvantageous occurrences such as a rise in the fluid temperature and excessive load on the motor.

Thus, the present invention, as described above with respect to a preferred embodiment thereof, overcomes the above described difficulties arising when only one control valve is used.

It should be understood, of course, that the foregoing disclosure relates to only a preferred embodiment of the invention and that it is intended to cover all changes and modifications of the example of the invention herein chosen for the purposes of the disclosure, which do not constitute departures

from the spirit and scope of the invention as set forth in the appended claim.

I claim:

1. A control valve comprising a pair of throttle valves adapted for connection in a common hydraulic circuit, each of said throttle valves comprising a housing provided with a throttle port and inlet and outlet channels communicating with the respective throttle port, each said housing being connected in tandem to the other such that each respective throttle port communicates coaxially with the other, and a common throttle-shaft regulator supported longitudinally in both of the coaxially communicating throttle ports, said common throttle-shaft regulator being provided with a pair of spaced recesses each cooperating with each of said throttle ports respectively such that a single manipulation of said common throttle-shaft regulator increases the open port area of one of said throttle ports and simultaneously decreases the open port area of the other of said throttle ports, one of said throttle valves including bypass means for bypassing a fluid when its associated

open port area is decreased by said regulator.

2. A control valve as claimed in claim 1 wherein each of said housings includes a front portion and a back portion, said inlet and outlet channels and said throttle port of each of said housings being identically arranged with respect to the respective front portion thereof, said housings being connected to one another in back-to-back relation.

3. A control valve as claimed in claim 1 wherein one of said throttle valves includes a bypass check valve.

4. A control valve as claimed in claim 1 wherein said housings are inverted 180° relative to one another.

5. A control valve as claimed in claim 1 wherein said pair of spaced recesses are each circumferentially disposed in said throttle-shaft regulator.

6. A control valve as claimed in claim 5 wherein said spaced recesses are each symmetrically disposed relative to the longitudinal axis of said throttle-shaft regulator.
